METHOD OF DEWAXING HYDROCARBON OILS

Leo D. Jones, Philadelphia, Pa., assignor to The Sharples Corporation, Philadelphia, Pa., a corporation of Delaware

Application November 27, 1933, Serial No. 699,918

9 Claims. (Cl. 196—19)

- The present invention relates to the removal of wax from hydrocarbon oils and is particularly concerned with the dewaxing of petroleum oil lubricating stock in such a manner as to remove the major portion of the wax from such stock and thereby produce a lubricating oil of desirably low cold test while substantially completely avoiding loss of oil by precipitation and separation with the removed wax.
- In current refinery practice wax is ordinarily removed from oil by filter pressing or by the use of Sharples continuous Super-Centrifuges in accordance with the method described in the patent to P. T. Sharples No. 1,351,265 of August 31, 1920, depending upon the nature of the wax to be removed. The wax contained in the petroleum fraction known as wax distillate is removed by chilling such distillate and passing it through filter presses to effect removal of precipitated wax, while the wax in the heavier distillates and residues is removed by the Sharples centrifugal process. The crystalline nature of the wax precipitated from the lighter fractions and from heavier fractions which have been subjected to cracking distillation renders difficult the discharge of such wax continuously from a centrifugal separator and the amorphous nature of the major portion of the wax precipitated from other heavier fractions precludes the separation of wax contained in these heavier fractions by filtration. Prior art practice has accordingly entailed the inconvenience inherent in careful fractionation to obtain a fraction which may be dewaxed by filter pressing and a heavier fraction which may be centrifugally dewaxed and it has also entailed the necessity of observing numerous other precautions in the treatment of the stock to be dewaxed in order to facilitate adequate wax removal by these methods.
- The present invention has had as its principal object the practice of a process by which petroleum fractions containing substantial proportions of both crystalline and amorphous wax may be dewaxed in a single operation. In view of the fact that it is applicable to stocks containing both crystalline and amorphous wax, the invention may be practiced without resort to the elaborate precautions heretofore necessary in the production of fractions of which the wax content consisted almost exclusively of crystalline and amorphous wax, respectively. It involves a method of operation by which a stock which may contain both of these types of wax is first diluted and chilled and the wax is thereafter removed from the oil by a process of subsidence separation whereby the individual precipitated wax particles are gathered into a cake during the removal of the major portion of the oil and the residual oil may thereafter be removed from the wax cake by drainage or straining through a suitable filter surface such as a pervious screen. In the preferred operation, both the step of removing the major portion of the oil by subsidence and separation and the step of removing the residual oil from the wax cake are performed in a single operating cycle in a centrifugal bowl of the extractor type, provided with a filter medium or screen for separating oil from the wax cake resulting from the gathering of wax during the subsidence separation.
- In connection with these operations, I prefer to use a centrifugal separator of the general type indicated in Fig. 2 of the patent to L. P. Sharples No. 1,761,593 of June 3, 1930. In the use of such a separator, the stock to be dewaxed is first diluted with a solvent or mixture of solvents adapted to maintain substantially all of the oil of the stock in a liquid state at a temperature sufficiently low to cause substantially all of the wax to be precipitated in solid state. The solvent used should be of different specific gravity than the oil or wax of the stock under treatment and in the preferred embodiment should be of higher specific gravity than these ingredients. The stock is preferably diluted at a temperature at which both oil and wax are soluble in the solvent and the mixture is thereafter chilled to a temperature sufficiently low to effectively precipitate the wax from the solution. The nature of the particular solvent mixture used for dilution of the oil has an important bearing upon the efficiency of operation. In the preferred embodiment of the invention, it is important that the solvent mixture have such a high solvent action upon all of the oil constituents of the stock that substantially all of the oil is retained in solution at the dewaxing temperature. An important feature of the invention resides in the discovery that a mixture of a chlorinated hydrocarbon solvent of relatively high specific gravity with a hydrocarbon diluent such as petroleum naphtha or a benzene homologue has an important effect in increasing the solubility of certain portions of the oil under treatment in the solvent mixture when such hydrocarbon is added to the chlorinated solvent in substantial proportions. Another important feature of the invention consists in the discovery that the addition of substantial proportions of one or more homologues of benzene to a chlorinated hydrocarbon solvent of the type indi-

cated above facilitates the precipitation of wax from the solution in such solvent of hydrocarbon oil, in a form adapted to produce, upon gathering of the wax, a porous wax cake well adapted for separation from residual oil by drainage or straining of the oil from the cake.

Other important features and advantages of the invention will be apparent from a reading of the sub-joined specification in the light of the attached drawing, in which:

The single figure represents a central longitudinal section of portions of a centrifugal machine adapted to be used in the practice of the invention.

Referring to the drawing by reference characters, the numeral 10 indicates an imperforate centrifugal bowl which is mounted for rotation upon a shaft 11 that is supported for rotation in bearings 12 and is provided with a pulley 13 or other similar driving element. Within the bowl 10 and co-axial therewith is a perforate or previous partition or screen 14 adapted to effect retention of wax while allowing the oil solution to flow therethrough, this partition or screen being spaced from the inner wall of the bowl 10 and held in spaced relation with respect thereto by a spacing member 15 which may be a coarse woven wire screen or grid adapted to permit free flow of liquid between the screen 14 and the inner circumference of the bowl 10. Within the bowl 10 and spaced from the outer end thereof is a disc 16 that extends radially inward from partition 14 and forms with the radially extending outer end of the bowl a liquid compartment 18.

The hub 20 of the bowl is surrounded by a disc affording a feed channel for liquid to be admitted to the bowl. The conically and radially extending portions 21 and 22 of this channel are provided with wings 25 and these wings act to accelerate liquid introduced into the bowl through the supply nozzle 23 and passage 24 in order that this liquid may attain substantially the speed of the bowl by the time it passes from the supply passage 24 into the bowl proper. The supply passage 24 leads into the main separating compartment 26 of the bowl. An adjustable skimming nozzle 28 is introduced into the compartment 18 of the bowl and this skimming nozzle acts to remove from the compartment 18 liquid which passes through the filter surface and under the dividing wall 16 into the compartment 18. By adjusting the position of the skimming nozzle the depth of liquid in the compartments 26 and 18 may be controlled. The bowl is surrounded by a casing 29 which supports the bearings 12. Conventional scraper and discharge mechanisms are used in effecting release and discharge of accumulated solids, the scraper mechanism being indicated generally at 31 and the discharge chute 60 at 32.

In the use of a centrifugal separator of the type illustrated in the dewaxing of a hydrocarbon oil stock, the stock is first dissolved in a chlorinated hydrocarbon solvent having a specific gravity very considerably higher than that of any constituent of the stock to be dewaxed. In this connection, best results have been obtained by the use of ethylene dichloride, although other chlorinated hydrocarbons such as methylene dichloride, propylene dichloride, dichlor ethylene or trichlor ethylene may be substituted for the ethylene dichloride. When compounds of this type are used alone and the solution is chilled to a temperature adapted to effect separation of wax from oil, a certain degree of extraction of naphthenic

from paraffinic hydrocarbon oils occurs and a certain proportion of the paraffinic hydrocarbon oil is enmeshed with the wax and separates from the chilled solution of hydrocarbon in connection with the separation of the wax from the major portion of the solution. Since this phenomenon results in loss of valuable paraffin oil and entails additional expense in connection with attempts to recover such oil, it is desirable that, if possible, it be avoided. An important feature of the present invention resides in the discovery that the loss of paraffin oil by reason of the solvent extraction effect of the heavy chlorinated solvent can be substantially completely avoided by the addition to such heavy chlorinated solvent of a substantial proportion of a solvent for the paraffinic constituents of the oil and such solvent should preferably be of relatively low viscosity. Thus, by the addition of amounts of naphtha or benzene constituting 25% or more of the volume of chlorinated solvent used, the solvent extraction effect of the chlorinated solvent in separating naphthenic from paraffinic oil is almost completely avoided.

Since the preferred practice of the invention involves an ultimate separation of oil from wax by a process by which the oil passes through a pervious surface by which the wax is retained, it is desirable that the solvent be of such a nature as to permit the precipitation of wax in a form in which it may not clog the screen. To this end it is necessary that a substantial proportion of the wax be of a sufficiently crystalline nature to avoid clogging of the pervious surface. An important feature of the invention consists in the discovery that the use of a homologue of benzene in conjunction with a chlorinated solvent of the type discussed above results in the precipitation of a substantial proportion of the wax in crystalline form and produces, upon gathering of the wax during separation of the major portion of the oil by subsidence, a coherent wax cake of sufficiently crystalline nature to be separated from the residual oil by drainage upon discontinuance of the subsidence separation operation and of sufficiently porous nature to permit it to be effectively washed after drainage. In the preferred practice of the invention a solvent mixture is therefore utilized which consists of 75% or less by volume of a heavy chlorinated hydrocarbon such as methylene dichloride and 25% or more of a benzene homologue.

The stock to be dewaxed is first diluted with a quantity of the solvent mixture discussed above amounting to between 2 and 4 times the volume of the stock under treatment at a temperature of approximately 100° F. The solution is thereafter chilled to a temperature of about -20° F. and is fed to the rotating centrifugal bowl 10 through the feed nozzle 23 and the supply passage 24. The skimming nozzle 28 is adjusted to position A during this stage of the cycle of operations. During continued feed of the solution to the centrifugal bowl, this solution will accumulate in the bowl until it extends radially inward in compartments 26 and 18 to the position occupied by the skimming nozzle 18. In view of the fact that liquid flows under the dividing wall 16 from compartment 26 to compartment 18, the liquid in these two compartments will be at the same level.

The precipitated wax which is suspended in the oil fed through the supply passage 24 to the centrifugal bowl, being of lower specific gravity than the oil solution, will pass radially inwardly

through the body of oil in the compartment 26 and form a coherent porous cake of wax at the inner surface of the body of oil rotating in that compartment. In view of the adjustment of the 5 skimming nozzle to the position A, the layer of liquid in the compartments 26 and 18 is of substantial depth during this stage of the operation and the accumulated layer of wax is accordingly maintained out of contact with the pervious surface 10 14 and has no tendency to clog this surface. After the feed of oil through the passage 24 and the removal of oil through the skimming nozzle A has taken place until the accumulation of a substantial quantity of wax at the inner surface 15 18 of the body of oil rotating in the compartment 26, the feed is discontinued and the skimming nozzle 28 is moved radially outwardly to the position indicated at B. This adjustment of the skimming nozzle effects removal of the residual oil 20 24 in the compartments 26 and 18 and the wax cake accordingly moves radially outwardly against the straining or filter surface 14.

The wax cake lying against the filter surface 14 is thereafter washed by spraying on the wax 25 an additional quantity of solvent mixture. This solvent mixture may be of the same character as that originally used in dilution of the oil and penetrates the wax cake and removes therefrom residual paraffinic oil constituents which may 30 have been retained in the wax cake by reason of the solvent extraction effect of the chlorinated hydrocarbon solvents. Other impurities are also removed during this washing operation. At the 35 conclusion of the washing operation the wax cake may be removed by manipulation of the scraper tool 31 in conventional manner and the machine is thereafter ready for a repetition of the cycle of operations. It will be evident from the above discussion that, by the practice of the 40 process of the invention, it is possible to effect removal of wax from an oil-wax mixture containing wax of both the crystalline and amorphous types and that the removal of wax from such a mixture can be continued for a substantial period 45 of time by utilization of a heavy solvent in connection with a centrifugal separator of the type illustrated because of the fact that the primary separation of wax from oil is a separation by subsidence and that the precipitated wax is 50 kept clear of the filter surface during this primary separation.

It will be further obvious that the use of the particular combination of solvents discussed above renders such a mode of operation feasible 55 and facilitates performance of the process by reason of the fact that the separation of paraffinic from naphthenic hydrocarbons is minimized in connection with the use of such a mixture. It will be further evident that a further important 60 advantage is attained in utilizing a mixture of solvents adapted to cause precipitation of a substantial proportion of the wax in crystalline form and that the utilization of this same mixture in the subsequent washing of the wax filtered from 65 the oil effects removal of any paraffinic hydrocarbon oil constituents which may have become enmeshed in the wax.

While the invention has been described by reference to particular apparatus, it will be evident 70 that certain broad aspects of the invention are applicable to treatment of hydrocarbon oils in other types of apparatus. Oil may be separated from wax, for example, by a combination of subsidence and filtering or straining operations in a centrifugal bowl of simpler design having

but a single separating compartment through which oil is projected through a peripherally arranged filter surface directly from the bowl, provided the rate of feed of oil to the bowl is maintained at a sufficient speed to maintain a body 5 of oil within the bowl and thus avoid accumulation of wax upon the filter surface during the primary separation by subsidence. In case a simpler bowl of such type is used, the rate of feed of oil may be diminished or the feed may 10 be discontinued after the accumulation of a substantial cake of wax. Such decrease or discontinuance of feed will result in movement of the wax cake against the surface and the residual oil will be removed from the wax by filtration as in 15 the case of separation by subsidence and filtration involving use of the apparatus of the preferred embodiment of the present invention.

Other modifications which may or may not involve the use of the specific apparatus described above fall within the spirit of the invention. It is possible, for example, to initially dilute the stock to be dewaxed by means of a solvent mixture of higher specific gravity than the stock, effect the primary separation of the major portion of the wax from oil in the manner above indicated and feed additional solvent mixture into the compartment 28 without changing the position of the discharge nozzle 28 until after the washing operation. In connection with an operation of this type, the solution used for the purpose of removing impurities from the wax penetrates the wax by reason of the fact that it possesses a higher specific gravity than the wax and this washing solution is discharged by the skimming nozzle 28 from the zone A of the auxiliary compartment 18. At the conclusion of the washing operation, the nozzle 28 may be adjusted from the position A to position B in order to effect removal of residual solvent and subsidence of the 35 porous wax cake against the member 14 from which it is thereafter removed, as above described. In connection with an operation of this type, the wax may be removed from the washing solution without first adjusting the nozzle 28 from the 40 position A to position B, if desired, or, as a still further alternative, the wax and washing solution or residual oil may be discharged together from the bowl and thereafter separated from each other. 50

The invention includes still other modifications of the specific procedure described above, provided the primary separation of wax from oil is attained by a process of subsidence and the secondary separation involves separation of residual oil from wax by a process of draining or filtration, or subsidence. It also includes all embodiments in which a primary separation of wax from oil is attained by a process of subsidence in a centrifugal bowl and a purification of the wax 60 is attained by a washing operation in the same bowl by passage of a washing liquid through the wax separated from the main body of oil by the subsidence separation. 55

Still further modifications will be obvious to 65 those skilled in the art and I do not, therefore, wish to be limited except by the scope of my subjoined claims.

I claim:

1. The method of dewaxing a hydrocarbon oil 70 stock which comprises diluting such stock with a solvent consisting of a low boiling liquid chlorine derivative of an aliphatic hydrocarbon having a higher specific gravity than the oil stock and with a hydrocarbon diluent of relatively low viscosity.

cosy in a proportion of at least 25% by volume of hydrocarbon diluent to 75% by volume of normally liquid chlorine derivative diluent, feeding the mixture so formed to a centrifugal bowl provided with a circumferentially extending filter surface at a temperature sufficiently low to effect precipitation of the major portion of the wax from the solution, separating the major portion of the wax from the solution by centrifugal subsidence while maintaining within the bowl a sufficient volume of oil to avoid accumulation of substantial quantities of wax upon the filter surface, and finally discharging residual oil from the bowl and thereby projecting precipitated wax against the filter surface and separating said wax from such residual oil by filtration.

2. The method of dewaxing a hydrocarbon oil stock which comprises diluting such stock with a solvent consisting of a low boiling liquid chlorine derivative of an aliphatic hydrocarbon having a higher specific gravity than the oil stock and with a hydrocarbon diluent chosen from the group consisting of petroleum naphtha and benzene in a proportion of at least 25% by volume of hydrocarbon diluent to 75% by volume of normally liquid chlorine derivative diluent, feeding the mixture so formed to a centrifugal bowl provided with a circumferentially extending filter surface at a temperature sufficiently low to effect precipitation of the major portion of the wax from the solution, separating the major portion of the wax from the solution by centrifugal subsidence while maintaining within the bowl a sufficient volume of oil to avoid accumulation of substantial quantities of wax upon the filter surface, and finally discharging residual oil from the bowl and thereby projecting precipitated wax against the filter surface and separating said wax from such residual oil by filtration.

3. The method of dewaxing a hydrocarbon oil stock which comprises diluting such stock with a solvent consisting of a low boiling liquid chlorine derivative of an aliphatic hydrocarbon having a higher specific gravity than the oil stock and with a hydrocarbon diluent consisting of benzene in a proportion of at least 25% by volume of hydrocarbon diluent to 75% by volume of normally liquid chlorine derivative diluent, feeding the mixture so formed to a centrifugal bowl provided with a circumferentially extending filter surface at a temperature sufficiently low to effect precipitation of the major portion of the wax from the solution, separating the major portion of the wax from the solution by centrifugal subsidence while maintaining within the bowl a sufficient volume of oil to avoid accumulation of substantial quantities of wax upon the filter surface, and finally discharging residual oil from the bowl and thereby projecting precipitated wax against the filter surface and separating said wax from such residual oil by filtration.

4. The method of dewaxing a hydrocarbon oil stock which comprises diluting such stock with a solvent of substantially higher specific gravity than said stock, feeding the mixture of oil and wax, at a temperature sufficiently low to effect precipitation of the major portion of the wax from the solution, to a centrifugal bowl provided with a circumferentially extending filter surface, maintaining a substantial quantity of oil within the bowl under a condition of liquid balance during the subsidence of wax to the inner zone of the body of material within the bowl, and finally withdrawing the oil from the bowl and thereby projecting precipitated wax against

the filter surface and separating wax from residual oil by a process of filtration.

5. The method of dewaxing a hydrocarbon oil stock which comprises diluting such stock with a solvent of substantially higher specific gravity than said stock, feeding the mixture of oil and wax, at a temperature sufficiently low to effect precipitation of the major portion of the wax from the solution, to a centrifugal bowl provided with a circumferentially extending filter surface, maintaining a substantial quantity of oil within the bowl under a condition of liquid balance during the subsidence of wax to the inner zone of the body of material within the bowl, withdrawing the oil from the bowl and thereafter passing a solvent through wax projected against said filter surface to remove residual impurities therefrom.

6. The method of dewaxing a hydrocarbon oil stock which comprises diluting such stock with a solvent of substantially higher specific gravity than said stock, feeding the mixture of oil and wax, at a temperature sufficiently low to effect precipitation of the major portion of the wax from the solution, to a centrifugal bowl provided with a circumferentially extending filter surface, maintaining a substantial quantity of oil within the bowl under a condition of liquid balance during the subsidence of wax to the inner zone of the body of material within the bowl, withdrawing the oil from the bowl and thereafter passing a solvent through wax projected against said filter surface to remove residual impurities therefrom, the solvent used in connection with the removal of residual impurities being of the same composition as that used in connection with the initial dilution of the oil.

7. The method of dewaxing a hydrocarbon oil stock which comprises diluting such stock with a solvent consisting of a low boiling liquid chlorine derivative of an aliphatic hydrocarbon having a higher specific gravity than the oil stock and with a hydrocarbon diluent of relatively low viscosity in a proportion of at least 25% by volume of hydrocarbon diluent to 75% by volume of normally liquid chlorine derivative diluent, feeding the mixture so formed to a centrifugal bowl provided with a circumferentially extending filter surface at a temperature sufficiently low to effect precipitation of the major portion of the wax from the solution, separating the major portion of the wax from the solution by centrifugal subsidence while maintaining within the bowl a sufficient volume of oil to avoid accumulation of substantial quantities of wax upon the filter surface, and finally discharging residual oil from the bowl and thereby projecting precipitated wax against the filter surface and separating said wax from such residual oil by drainage.

8. The method of dewaxing a hydrocarbon oil stock which comprises diluting such stock with a solvent of substantially higher specific gravity than said stock, feeding the mixture of oil and wax, at a temperature sufficiently low to effect precipitation of the major portion of the wax from the solution, to a centrifugal bowl, maintaining a substantial quantity of oil within the bowl under a condition of liquid balance during the subsidence of wax to the inner circumference of the body of oil within the bowl and the removal of the major portion of the oil fed to the bowl from the wax, and finally separating residual oil from wax by a process of drainage.

9. The method of dewaxing a hydrocarbon oil

stock which comprises diluting such stock with a solvent of substantially higher specific gravity than said stock, feeding the mixture of oil and wax, at a temperature sufficiently low to effect precipitation of the major portion of the wax from the solution, to a centrifugal bowl provided with a circumferentially extending filter surface, maintaining a substantial quantity of oil within the bowl during the subsidence of wax to the inner circumference of the body of

oil within the bowl, feeding a washing solution of higher specific gravity than the wax to the bowl and passing said solution through the precipitated and subsided wax within the bowl while maintaining said wax clear of the filter surface 5 and finally withdrawing residual liquid by straining and thereby effecting projection of precipitated wax against the filter surface.

LEO D. JONES. 10
